UNITED STATES PATENT OFFICE.

WILLIAM E. WINANT, OF WASHINGTON, DISTRICT OF COLUMBIA.

CONVEYER.

SPECIFICATION forming part of Letters Patent No. 718,745, dated January 20, 1903.

Application filed January 8, 1902. Serial No. 88,876. No model.

To all whom it may concern:

Be it known that I, WILLIAM E. WINANT, of Washington, in the District of Columbia, have invented certain new and useful Improvements in Conveyers; and I hereby declare that the following is a full, clear, and exact description thereof, reference being had to the accompanying drawings, which form part of this specification.

This invention is an improvement in conveyers, and has especial reference to devices for transporting ammunition from the magazine to the guns or to the several decks on which guns are located when used on warships or from the magazines to the guns of forts. It is especially designed for use on warships wherein the magazines are located in the hold at the ends of the vessel, while the guns are located several decks above and in some cases a hundred feet away from the magazine. The conveyer is intended to transport all kinds of ammunition from the magazine to the gun direct, and any ammunition that is not required at the guns passes on and is returned to and automatically delivered in the magazine.

The objects of the present invention are, first, to provide a conveyer by which ammunition is kept constantly going to and by the gun-station, and if not desired at the gun is immediately returned to the magazine and by which ammunition can be supplied to one gun or a plurality of guns at the maximum rate at which the guns can be fired; second, to provide a conveyer by which all kinds of ammunition can be conveyed from the magazine to the gun direct without manhandling in transit and which automatically picks up all kinds of ammunition placed on the loader in the magazine and automatically conveys it to the gun-station, the receipt of ammunition at the gun-station being controlled solely by the gun captain; third, to provide a conveyer which after it has carried ammunition to the gun, if it is not desired at the gun, will return it to and automatically deliver it in the magazine and by which unused or drill ammunition may be returned from the gun or main deck of a vessel to and automatically delivered in the magazine; fourth, to provide novel receiving or unloading devices for removing or taking the ammunition from the

conveyer while it is in motion and while in motion will safely deliver ammunition on a receiving-table at the gun without having to be slowed down or stopped. The several objects are practically attained in the present invention, and the accompanying drawings illustrate one form and arrangement of ammunition-conveyer embodying my invention as applied to a war vessel, and I will describe the invention as illustrated therein, referring to the claims following description for a summary of the various novel features and combinations of parts upon which I desire protection, for although I consider the conveyer shown in the drawings the best and most practical form known to me it will be obvious that many changes can be made in the mechanical construction and arrangement of parts entire within the scope of my present invention which I do not consider restricted to the particular embodiment and application thereto illustrated in the said drawings.

In the drawings, Figure 1 is a longitudinal sectional elevation of a portion of a warship showing one of my ammunition-conveyers therein. Fig. 2 is a plan view of Fig. 1 with the main deck removed. Fig. 3 is an enlarged side elevation of the portion of the conveyer apparatus within the magazine. Fig. 4 is an enlarged plan view of the loading and unloading apparatus in the magazine. Fig. 5 is an enlarged plan view of the conveyer-propelling mechanism. Fig. 6 is an enlarged view through the conveyer apparatus in the second gun-station. Fig. 7 is a plan view of so much of the conveyer as is shown in Fig. 6. Fig. 8 is an enlarged plan view of one of the carriers. Fig. 9, a transverse section therethrough, Fig. 10 an end view thereof. Figs. 11 and 12 are detail top and end views of the unloading tripping mechanism. Fig. 13 is a detail view of one of the carrier-chains.

V designates part of the hull of a warship, having an upper or main deck V¹, a deck V², below which is a protective deck under which are the boiler-room V⁴, bunkers V⁵ V⁶, dynamo-rooms V⁷, and magazines, one, V⁸, being shown. The arrangement of these compartments will of course vary with the character and build of the vessel, and I have simply chosen this

cular build of vessel to illustrate one practical application of the invention. Between the decks V' V^2 are a number of gun inclosures or stations, Nos. 1, 2, and 3, arranged substantially horizontal series, and in each station is located a gun, to which ammunition to be supplied from the magazine V^3 , and for simplicity of explanation it is assumed that each gun is of same size and uses the same kind and quantity of ammunition. Gun-inclosure No. 1 is located vertically above the magazine, so that ammunition can be taken from the magazine through a vertical trunk into inclosure No. 1, within which, above the upper end of trunk v , is conveyer-head casing B , which should be made of stout metal capable of withstanding severe blows and shocks without injury to or derangement of the conveyer therein. In the other inclosures, Nos. 2 and 3, similar conveyer-head casings B' B^2 are formed. Each conveyer-head casing has an opening b in one side for the delivery of ammunition, and may have an opening in its opposite side for the loading of ammunition onto the conveyer, as hereinafter explained. The casings B B' are connected or communicate through a horizontal trunk v' , formed just below the gun-deck V^2 , and casings B' B^2 are similarly connected by a like trunk v^2 below the gun-deck V^2 . From the last inclosure, No. 3, a vertical conveyer-trunk v^3 leads downward to and below the protective deck V^3 , where it connects with the aft end of a horizontal trunk v^4 , that leads forward through and above the boiler and dynamo rooms to the upper end of the magazine V^4 . The trunks v v' v^2 v^3 v^4 and casings B B' B^2 together form a continuous but tortuous conveyer trunk or passage leading from the magazine successively to the several gun-stations and back to the magazine, and through this passage an endless ammunition-conveyer is traveled, said conveyer being constructed and arranged as follows:

In a chamber V^3 below the magazine are a pair of suitably-spaced sprocket-gears C C' , keyed on a shaft C' , journaled in a frame C^3 , fixed to the lower platform of the magazine, these gears being driven by power applied to shaft C' , as hereinafter explained. Under these sprockets run endless roller sprocket-chains D D' , which pass from sprockets C to and under grooved pulleys E E' , mounted on a shaft E' , supported in vertically-adjustable bearings E^2 , suitably supported or suspended within the chamber V^3 , said pulleys being vertically below the trunk v , so that the sprocket-chains can pass up vertically through said trunk to and over similar grooved pulleys F F' , mounted on a shaft F' , journaled in the casing B . From pulleys F the chains descend to and under grooved pulleys G on a shaft G' , journaled in the forward end of trunk v' just below casing B , and from pulleys G the chains pass back to and under sprocket-wheels H H' on a shaft H' , journaled in the rear end of trunk v' just below casing B' . Thence

the chains pass up to and over pulleys I I' on a shaft I' , journaled in the upper end of casing B' , thence down to and under pulley J on a shaft J' , journaled below casing B' in the forward end of trunk v^2 , thence back to and under sprocket-wheel K on shaft K' , journaled in the aft end of trunk v^4 , thence up and over pulleys L on a shaft L' , journaled in the upper end of casing B^2 . Thence the chains pass down through trunk v^4 to and under pulleys M on shaft M' , journaled in the aft end of trunk v^4 . Then the chains lead forward over pulleys N N' on a shaft N' , journaled transversely of the trunk v^4 , and onto and over pulleys O O' on a shaft O' in the magazine V^4 above the driving-sprockets C , from which the chains pass back to said sprocket. Thus the chains make a complete circuit from the magazine to and through each casing B B' B^2 in the several gun-inclosures and back to the magazine, traveling a tortuous but endless path. These chains may be of any suitable kind. I preferably employ what are known as the "Jeffrey patent roller link-chains," the links of which are provided with rollers which relieve the chain of much friction. The horizontal leads of the chains within the trunks v , v' , and v^4 may be supported by horizontal angle irons or ways P P' P^2 , respectively, as shown, to prevent sagging of these portions of the conveyer when loaded carriers are passing thereby.

Between the opposite chains D D' at uniform distances apart are hung the ammunition-carriers Q Q' , which are preferably open at top and one side, and bottoms are composed of a series of equidistant fingers Q' , which are preferably slightly concaved, as shown, so as to prevent shells or powder-tanks slipping from the carriers *en route*. The backs and ends of these carriers may be stamped from sheet-steel in one piece Q^3 , and the fingers may be separately formed and attached to the lower edge of the back of carrier, as shown. In order to suspend the carriers pivotally from the chains D D' , some of the links of the latter are provided with inwardly-projecting horizontally-disposed lugs d , provided with enlarged heads or flanges d' . These heads are fitted in split bearings q , which are secured to the ends of the carriers, so that the carriers are thus freely suspended from and between chains D D' and at the same time form a bond between the chains. The sprockets C C' being fast on same shaft and being the propelling means for the chains the latter are kept and moved in unison, so that the carriers always hang freely therebetween and always maintain the same position, the bearings q being so located on the ends of the carriers that the latter will by gravity maintain their horizontal position loaded or unloaded. The pintles d are long enough to clear the flanges on the pulleys, and in passing the pulleys F I L N O the carriers pass between the pulleys, but over their shafts. To prevent accidental

tipping of the carriers Q in the vertical trunks v v³, the carriers have vertically-grooved guides q' attached to their ends in front of the bearings q and vertical lips q² attached to their ends in rear of the bearings. The guides q' are adapted to engage vertical guide-rails R in the trunk v and casings B B' B² as the carriers pass upwardly therein, and lips q² are adapted to engage vertical grooved guides R' in the casings B B' B², trunk v³, and magazine as the carriers descend therein, as shown. In the horizontal portions of the several trunks the bottoms of the carriers run so near the bottoms of the trunks that accidental tipping is impossible.

I prefer to employ electricity as the motive power for operating the conveyer, but do not limit myself thereto. As shown, a gear C⁴, keyed on shaft C', meshes with a pinion C⁵ on a counter-shaft C⁶, on which is keyed a large gear C⁷, meshing with and driven by a small pinion C⁸ on the armature-shaft of an electric motor C⁹, which is connected with the generating apparatus on the ship, suitable controlling apparatus being provided for regulating the speed of the motor and for changing its speed, if desired. Such apparatus being commonly known and forming no part of the present invention, I deem it unnecessary to explain or illustrate it herein. The motor should be of sufficient power to propel the conveyer loaded at any desired predetermined rate of speed with certainty and uniformity.

The conveyer is always loaded on the ascending side and is unloaded on the descending side, and the preferred means for loading and unloading the conveyer are as follows: The loading-table S is located in the magazine V⁸ beside the vertical run of the conveyer therethrough. The end of this table next the conveyer is provided with eyes s, through which passes a rock-shaft s', and on this shaft are fixed a series of fingers S', which when lowered into a horizontal position extend into the path of the conveyer and will come intermediate the fingers Q' on the carriers Q, the fingers of the carriers passing between the fingers on the loading-table, as shown in Fig. 4. When not loading, the shaft s' can be turned, so as to raise fingers S' into a vertical position out of the way of the carriers. When a shell T or a powder-tank t is placed on the table and shoved onto the fingers S', the latter being lowered, as shown in Fig. 3, the first ammunition-carrier that passes the loading-table will lift the shell or tank therefrom and carry it upward and into the several gun-stations until it is taken from the carrier, and if not taken therefrom it will be brought back into the magazine and there be removed from the carrier by the unloading device in the magazine, which consists of an inclined table U, having a series of fingers U' attached to one end next the conveyer and adapted to come intermediate the fingers Q' of the carriers as the latter descend, so that

the shell or tank on the carrier will remain suspended on the fingers U' while the unloaded carrier passes onward. The unloader U and fingers U' are preferably set at a sufficient angle to cause the shell or tank to slide down out of the way of the next carrier; but in practice there should be crews of men stationed at the loading and unloading tables to supply ammunition to the former and remove any ammunition delivered to the latter to prevent choking up of the unloading-table.

In action or at drill the ammunition would be taken from the carrier at some one of the gun-stations, as desired. For this purpose each casing B B' B² is provided with an ammunition taker or receiver, consisting of a table W, preferably slightly inclined and located adjacent to the opening b in the casing, and to the inner end of the table is pivoted a horizontal shaft W², on which are fixed a series of fingers W', adapted to come intermediate the fingers Q' on the carriers Q when the shaft W² is rocked so as to throw fingers W' into the casing, as shown in Figs. 1 and 5. The shaft W² is provided with an operating-handle W³, carrying a weight W⁴, by which the shaft will be normally held with fingers W' out of operative position. When the gun captain desires ammunition, he raises lever W⁵, throwing fingers W' into the path of the carriers Q (see Fig. 6) and holds the lever until the next descending carrier passes, leaving its burden upon fingers W', which are then thrown upward and outward, discharging the ammunition onto the table W. Thus the gun captain can take ammunition as often as he needs it. The shaft W² is automatically rocked to throw the fingers W' out of the casing each time a load is received on the fingers W', as follows, (see Figs. 11 and 12:) On the inside of each casing B B' B² just below opening b is journaled a rock-shaft w, having on its inner end a crank-arm w', carrying at its free end a roller w², adapted to bear against the under side of one of the fingers W' and loosely confined thereto by a guard-loop w³, as shown in Fig. 12. On the other end of shaft w is keyed a segment w⁴ which meshes with a similar segment w⁵ on the end of a trip-lever w⁶, pivoted at w⁷ and projecting inwardly close beside the run of the adjacent chain D. (See Figs. 12 and 6.) When the fingers W' are thrown inward into receiving position, crank w' is depressed, rocking shaft w and throwing lever w⁶ up into the position shown in Fig. 12, where it will be engaged by a trip-roller d⁸ on a pin d on one of the links of the adjacent chain D such a trip-roller being attached to the chain adjacent to every carrier Q and in such position that just after such carrier has passed below the fingers W', leaving its burden thereon, roller d⁸ strikes trip-lever w⁶, depresses the latter, thereby rocking shaft w and throwing arm w' upward, lifting finger W' out of the way of the next carrier into th

position shown in dotted lines, Fig. 12, and weight W^4 holding them thus until the gun-captain throws them inward again by hand, as above described. To prevent the ammunition flying off the carriers at the forward turns of the conveyer, guards $Y Y^2$ may be placed at proper points in the trunk and casings, as shown in Fig. 1. The speed of the conveyer in action should be such that the maximum number of pieces of ammunition at which the gun can be fired per minute should be constantly passing the several ammunition-receivers in the respective gun-stations, thereby allowing each gun captain to take off ammunition as required, the ammunition that is not taken passing on and being returned to and automatically delivered in the magazine. In practice the charges of powder and shell should be loaded alternately on the conveyer, so that the captains can get the desired supply of ammunition.

The conveyer may be utilized for loading the magazine or "striking down" the ammunition by providing loading-tables at any suitable points in the ascending trunks. Such tables X are shown in connection with casings $B B'$. These tables X constitute the doors or closures for openings b' in the sides of the casings when not in use and are hinged to the casings at the lower edges of the openings. When opened and dropped to a horizontal position, as shown in Fig. 5, they are supported by legs X^2 . At the lower or inner end of table X is pivoted a short plate X' , which when the carriers Q pass (ascending) will be lifted out of the way by the rear side of the carriers, as indicated in dotted lines in Fig. 6. Opposite the plate X' are a series of fingers x , pivoted on brackets x' , attached to division-plates B^3 or other suitable supports within the casings $B B'$. The fingers x when raised to vertical position, as shown in dotted lines in Fig. 6, are out of the way and may be held by catches x^2 and are so held during the operation of the apparatus for carrying ammunition to the gun-stations. If, however, it is desired to strike down or return ammunition to the magazine, the doors X are opened and fingers x lowered, as shown in full lines in Fig. 6. The fingers x in this position (like fingers $S', T',$ and W') will lie or pass between the fingers Q' of the carriers. The ammunition can then be shoved onto fingers x and will be lifted therefrom by the next ascending carrier Q and taken on and back to the magazine.

From the foregoing description it will be clear that by my improved apparatus ammunition can be conveyed from the magazine to one or more gun-stations successively and can be taken therefrom at the will of the gun-captains, or if not taken therefrom the ammunition will be returned to the magazine; also, that the apparatus can be utilized for loading the magazine or for returning to the magazine any unused ammunition in the several stations, that the only man-handling of

the ammunition required is that of placing it upon the loading-fingers or removing it from the unloading-tables, that the device is quite compact and greatly economizes space, which is most important in vessels, and that its speed can be easily regulated by varying the current applied to the motor. The shafts of sprockets $C, H,$ and K may be provided with cranks or other suitable means for turning them by hand-power, so that in cases of emergency or any breakage of the mechanical motor the conveyers can be propelled by manual labor.

While I have described the carriers as provided with load-supporting "fingers" at bottom, it is obvious that they might accurately be described as having open slots in their bottoms through which the loading and unloading fingers or devices can pass, the effect and operation being identical in either event.

The invention, while designed and primarily intended for use as an ammunition hoist or conveyer, may obviously be usefully employed and readily adapted for handling other material, and therefore I do not restrict myself to the specific combinations and features of construction and particular application or utilization of the invention herein shown and described, nor do I restrict myself to the employment of electricity as the motive power for the conveyer.

Having thus described my invention, what I therefore claim as new, and desire to secure by Letters Patent thereon, is—

1. The combination of a magazine, two or more gun-stations above the same arranged in substantially horizontal series and endless chains leading from the magazine to the several gun-stations, pulleys for carrying and guiding said chains, and means for propelling them; a series of carriers suspended from and between the chains so as to maintain a horizontal position, said carriers having a series of load-carrying fingers forming their bottoms; with means for loading the carriers within the magazine, and means for taking the loads from the carriers in each of the gun-stations, said means comprising fingers adapted to be thrown into the path of the carriers and to take the load therefrom as the latter descend, substantially as described.

2. The combination in an ammunition-carrier, of endless chains leading from the magazine to and through the several gun-stations and return, and means for causing said chains to make bends or loops in the gun-stations, and a series of carriers suspended by and between the chains; with means for loading the carriers within the magazine, and ammunition-takers in the gun-stations, adapted to be thrown into the path of the carriers at the descending side of the bends, and means for throwing the takers out of the way when the carriers have passed, substantially as described.

3. The combination in an ammunition-carrier, of endless chains leading from the maga-

zine to and through the several gun-stations and return, means for causing said chains to make vertical bends or loops in the gun-stations, and a series of carriers suspended by and between the chains, said carriers being open at one side, and having their bottoms formed by transverse fingers; with means for loading the carriers within the magazine, and the ammunition-takers in the gun-stations, comprising fingers adapted to be thrown into the path of the carriers at the descending side of the bends, and means for throwing the fingers out of the way when the carriers have passed, substantially as and for the purpose described.

4. The combination of a traveling-conveyer carrier having an open side, and a series of transversely-disposed load-supporting fingers for its bottom; with load receiving or taking fingers normally outside the path of the carrier, and manually-controlled means for moving said fingers into the path of the carrier, a rock-shaft having a crank-arm underlying the fingers, and a trip-lever and connections for operating the rock-shaft, and a trip-lug moving with the carrier adapted to engage said lever when the taking-fingers have received the load from the carrier, substantially as described.

5. The combination of a traveling-conveyer carrier having an open side and a series of transversely-disposed load-supporting fingers for its bottom; with a load receiver or taker, comprising a table, a series of fingers hinged thereto normally outside the path of the carrier, and manually-controlled means for moving said fingers into the path of the carrier, a rock-shaft beside the taker having a crank-arm underlying the fingers, and a trip-lever and connections for operating the rock-shaft, and a trip-lug moving with the carrier adapted to engage said lever when the taking-fingers have received the load from the carrier, substantially as described.

6. The combination of an endless conveyer, the carrier pivotally hung thereon, having an open front and a series of transversely-disposed fingers forming its bottom, and a load-receiver, comprising a table, a rock-shaft journalized thereon, a series of fingers fixed on said shaft, adapted when the shaft is rocked in one position to enter the path of the carrier and to pass between the carrier-fingers and take the load therefrom, and a weighted lever for rocking said shaft and holding the taking-fingers normally out of operative position; with a rock-shaft beside the receiver, a segment thereon, a toothed trip-lever engaging the segment, and a crank-arm on said rock-shaft for throwing the receiving-fingers out of the path of the carrier when they have taken a load, and a trip-lug on the chain for operating said trip-lever, all substantially as and for the purpose set forth.

7. An endless ammunition-conveyer comprising two parallel endless chains, and a series of gravitating carriers pivotally connect-

ed to and suspended between said chains and constantly maintaining by gravity a horizontal position both on the ascending and descending runs of the carrier; said carriers being closed on one side and both ends, open on the other side and having transverse fingers attached to the side forming its bottom, with means for loading the carriers while they are moving vertically upward and for unloading them while they are moving vertically downward, substantially as described.

8. In a conveyer, a carrier open at one side and having load-sustaining fingers attached to the closed side and forming its bottom, and means for moving said carrier in an endless path; with an unloading device beside the downward run of the conveyer and normally out of the path of the carrier, said device having fingers adapted to come between the fingers of the carrier and take the load therefrom while the carrier is descending, and manually-operated means for throwing said unloading device into the path of the carriers.

9. The combination of an endless conveyer a series of carriers pivotally suspended therefrom provided with load-sustaining fingers, a set of fingers whereby the carriers may be loaded during their upward movements, and a set of fingers beside the descending run of the conveyer, for unloading the carriers during their downward movements; with manually-operated means for throwing said unloading-fingers into the path of the carrier and automatically-operated means for throwing them out of the path of the carriers after receiving a load therefrom, substantially as described.

10. In a conveyer, the combination of a pair of parallel endless chains, carriers pivotally suspended therefrom and therebetween adapted to constantly maintain a horizontal position, each carrier being open at one side and having parallel load-supporting finger attached to its other side and forming its bottom; with an unloading device having finger adapted to project between the chains and into the path of the carriers and come intermediate the fingers thereon, substantially as described.

11. In a conveyer, the combination of a pair of parallel endless chains, carriers suspended therebetween and therefrom and constantly maintaining a horizontal position on both the vertical and horizontal runs of the chains; each carrier being open on one side and having a series of parallel load-supporting fingers attached to its other side and projecting transversely of the carrier to form its bottom with a loading device, and an unloading device, each having a series of fingers adapted to project between the chains into the path of the carrier and come intermediate the fingers thereon, substantially as described.

12. In an ammunition-conveyer, the combination of the magazine, the parallel endless chains passing therethrough, and carriers pivotally suspended from and between said chain

each being open at its front side and closed at rear and both ends and having a series of parallel load-sustaining fingers projecting from the rear side thereof; with a loading device and an unloading device in the magazine, each device having a series of fingers adapted to project between the chains into the path of the carriers and to come intermediate the fingers thereon, so that the carriers can take ammunition from the loader while they ascend, and deliver ammunition to the unloader while they descend, substantially as described.

13. The combination of a series of stations, and an endless conveyer leading successively to the several stations; and a series of carriers on said conveyer each carrier being open at its front side, and closed at its rear side, a series of forwardly-projecting load-sustaining fingers attached to said rear side with an unloading device in each station located normally outside the path of the conveyer, and manually-controlled means for throwing the unloading device in any station into the path of the conveyer whereby loads may be taken from the conveyer in any station at the will of the operator therein, substantially as described.

14. In an ammunition-conveyer, the combination of a magazine, a series of gun-stations, and an endless conveyer leading from the magazine to the several stations and return, and a series of carriers on said conveyer each carrier being open at its front side, and closed at its rear side, a series of forwardly-projecting load-sustaining fingers attached to said rear side; with means for loading the conveyer-carriers in the magazine, and an unloading device in each station located normally outside the path of the conveyer, and manually-controlled means for throwing the unloading device in any station into the path of the conveyer.

15. In an ammunition-conveyer, the combination of a magazine, a gun-station, endless chains leading from the magazine to the station and back to the magazine, and carriers pivotally suspended between the chains open at front side and closed on both ends and rear side having load-supporting fingers projecting from the rear side and forming the carrier-bottom; with an unloading-table in the gun-station having tilting fingers normally standing outside the path of the carriers and manually-controlled means for tilting the fingers into the path of the carriers to take ammunition therefrom, substantially as described.

16. The combination of a magazine, a series of gun-stations, an endless conveyer composed of parallel chains leading from the magazine successively to the several stations and back to the magazine, said conveyer making loops or bends in each station, and carriers pivotally suspended between the chains having load-supporting fingers at bottom; with an unloading-table in each gun-station having hinged fingers adapted to be tilted to a posi-

tion intermediate the fingers on the carriers and manually-operated means for throwing the fingers into operative position, substantially as described.

17. The combination of a magazine, a series of gun-stations, an endless conveyer leading from the magazine to the several gun-stations and making a bend in each station, and carriers on the conveyer pivotally suspended so as to constantly maintain a horizontal position; with an unloading device in each gun-station standing normally out of the path of the carriers, and manually-controlled means for moving the unloading device in any gun-station into the path of the carriers to take ammunition therefrom at the will of the gun captain, substantially as described.

18. The combination of a magazine, a series of gun-stations above the same and endless chains leading from the magazine to the several gun-stations, pulleys for carrying and guiding said chains both on the vertical and horizontal runs of the conveyer, means for propelling the chains, and a series of carriers suspended from and between the chains so as to constantly maintain a horizontal position on the vertical and horizontal runs of the chains; each carrier being open at its front side and closed at the rear side and having a series of transversely-arranged fingers attached to the rear side with manually-controlled means for taking the loads from the carriers in any one of the gun-stations as desired by the gun captain therein, substantially as described.

19. In an ammunition-conveyer, the combination of a vertical trunk, an endless conveyer passing therethrough provided with carriers, an opening at the outer side of the trunk and a loading device hinged to the inner side of the trunk opposite said opening onto which loads may be placed when "striking down" ammunition, substantially as described.

20. The combination with a conveyer-carrier, having one side open and load-supporting fingers attached to its solid side, and a loading-table at the outer side of the conveyer-passage; with a series of loading-fingers hinged to the side of the conveyer-passage opposite the loading-table onto which fingers loads may be placed when "striking down" ammunition substantially as described.

21. The combination of the endless conveyer and carriers thereon each open at one side and provided with load-sustaining fingers attached to its single side and forming its bottom; with a loader attached to the side of the conveyer-casing adjacent to the open sides of the carriers, at the ascending side of the conveyer, said loader having a series of fingers adapted to come between the fingers of the carriers and permit the latter to take loads therefrom as they ascend, substantially as and for the purpose described.

22. In an ammunition-conveyer, the com-

5 combination of the endless conveyer leading from the magazine to the gun-station, and making a bend in such station, ammunition-carriers on said conveyer open at one side and provided with parallel load-sustaining fingers attached to its solid side and projecting therefrom, and a loading-table at the ascending side of the bend; with ammunition-supporting fingers attached to the inner side of the 10 conveyer casing or trunk, opposite the loading-table, and adapted to pass between the fingers of the carriers as the latter ascend whereby the carriers are enabled to take loads from the fingers, substantially as set forth.

15 23. In a loading apparatus, the combination of an endless conveyer, a series of carriers pivotally suspended therefrom so as to constantly maintain a horizontal position, a loading-table at the ascending side of the 20 conveyer, a movable carrier-loader within the conveyer-casing, at the ascending side thereof, and opposite the table onto which loads are placed preparatory to being removed by the carriers, the loads being taken from the 25 loader by the carriers as they ascend and

taken upwardly and then down to the discharging-point, substantially as described.

24. In an ammunition-conveyer, the combination of an endless conveyer, carriers suspended therefrom to maintain a horizontal 30 position, said carrier being open on its front side and closed at rear side and having a series of load-sustaining fingers projecting from its rear side; with a loading-table located at the ascending side of the conveyer and provided with a series of movable fingers adapted to project into the path of the carriers as they ascend and to support loads to be removed by the carriers, said fingers being movable out of the path of the carriers when 35 it is not desired to load them substantially as and for the purpose described.

In testimony that I claim the foregoing as my own I affix my signature in presence of two witnesses.

WILLIAM E. WINANT.
